UNITED STATES PATENT OFFICE.

WILLIAM H. PEARSON, OF WATERTOWN, NEW YORK.

PARKING LIGHT.

Application filed October 26, 1922. Serial No. 597,129.

To all whom it may concern:

Be it known that I, WILLIAM H. PEARSON, a citizen of the United States, residing at Watertown, in the county of Jefferson and State of New York, have invented certain new and useful Improvements in Parking Lights, of which the following is a specification.

My invention relates to an identification and parking light for automobiles, and one of the objects of the invention is to provide a device of this character which will be cheap to manufacture, easy to assemble, compact in arrangement, and moisture and dust proof when assembled.

A further object is to provide a construction having easily removable transparent panels, which can be used for purposes of identification.

With these general objects in view, my invention consists in certain novel and peculiar features of construction and combination of parts as hereinafter described and claimed, and in order that it may be fully understood, reference is to be had to the accompanying drawing in which—

Figure 1 is a front elevation of the parking light;

Fig. 2 is a side elevation;

Fig. 3 is a vertical transverse section; and

Fig. 4 is a vertical longitudinal section of the body of the light.

Referring to the drawing, 2 is the base plate adapted to be secured to the fender 3 of the vehicle by fastening devices 4. The said plate is provided with a screw threaded opening 5 for engagement by the screw threaded end 6 of the standard 7, which has an electric light bulb 8 secured to its upper end in any suitable manner. The electric wiring 9 passes through and is concealed from view by the standard 7.

The upper end of the said standard is screw threaded at 10 and engages a screw threaded opening 11 in the cylindrical body member 12. The body member has longitudinal openings 13 and 14 on its front and rear

adapted to be covered respectively by white and red transparent panels 15 and 16 which are preferably celluloid and which may bear suitable identification marks. For detachably holding the said panels in position, I provide tag slip plates 17 and 18 at the top and bottom of the said openings, the said plates being constructed of metal, secured to the body member by screws 20 and having offset retaining lips 19.

The body member 12 is screw threaded at each end to cooperate with screw threaded end caps 21 and 22 which have openings 23 and 24 therein for the passage of light. Transparent plates 25 and 26, which may bear suitable indicia, such as the initials of the driver of the car, are inserted between the ends of the body 12 and the end caps and are thus securely held in place when the caps are screwed up tight.

From the above description it will be apparent that I have produced a device of the character enumerated as desirable and while I have illustrated the preferred form of the invention, it will be understood that I reserve the right to all changes properly falling within the spirit and scope of the appended claim.

What I claim as new and desire to secure by Letters Patent of the United States is:

A parking light comprising a base plate, means for securing the same to the fender of a vehicle, a standard in screw threaded engagement with the base plate, a light located on the upper end of the standard, a cylindrical body member surrounding the light and in screw threaded engagement with the upper end of the standard, elongated openings in the front and rear of the said body member, removable transparent panels secured therein, screw threaded ends on the cylindrical body member, end caps in screw threaded engagement therewith and transparent plates between the ends of the body member and the said end caps.

In testimony whereof I affix my signature.

WILLIAM H. PEARSON.
